UNITED STATES PATENT OFFICE

2,482,361

SYRINGE

Frank S. Parrigin, Evansville, Ind.

Application May 5, 1947, Serial No. 746,129

2 Claims. (Cl. 128—241)

1

This invention comprises novel and useful improvements in a syringe, and more specifically pertains to an improvement upon the invention set forth in the prior patent of J. W. Brunett, Patent No. 1,751,507 of March 25, 1930.

This invention is primarily concerned with providing an improved and highly efficient construction of the syringe needle which has been advantageously adapted for injecting douche fluid into the vagina and draining the same therefrom, although it is not to be so limited and may be employed as a surgical instrument to facilitate the cleansing of any bodily cavity.

The principal purpose of this invention therefore resides in providing a syringe for injecting a spray into a bodily cavity, and for withdrawing the same.

A further object of the invention is to provide a syringe in accordance with the preceding object which has an improved construction of liquid sealing for temporarily sealing and enclosing a bodily cavity during treatment by the spray.

Another important purpose of the invention consists in providing an instrument in accordance with the above-mentioned objects wherein concentric passages are provided in the body of the instrument for introducing and withdrawing a medicament or spray from a bodily cavity.

A further important purpose of the invention to be specifically enumerated herein, resides in the provision of an improved syringe which shall be of compact and simple construction, with a spray nozzle readily removable for purposes of cleansing or purposes for replacement; and wherein the syringe may be equally useful for manual operation or from a power source for supplying and withdrawing the spray as desired.

These, together with various ancillary objects of the invention which will later become apparent as the following description proceeds, are attained by this device, preferred embodiments of which have been illustrated by way of example only in the annexed drawings, wherein:

Figure 1 is an elevational view showing the syringe according to a first embodiment of the invention;

Figure 2 is an enlarged elevational view of the syringe nozzle tube removed therefrom;

Figure 3 is a horizontal sectional view taken substantially upon the plane of the section line 3—3 in Figure 2 and showing the concentric construction of the nozzle;

Figure 4 is a vertical sectional view through the form of the invention shown in Figure 1, showing the interior construction and passage 55

2

arrangement thereof, this view being taken substantially upon the plane of the section line 4—4 of Figure 3;

Figure 5 is a horizontal sectional detail view taken substantially upon the plane of the section line 5—5 of Figure 4;

Figure 6 is a horizontal sectional view taken substantially upon the plane of the section line 6—6 of Figure 4 and showing further details of 10 the passage construction of the device;

Figure 7 is a view similar to Figure 4 of a second modification of the invention;

Figure 8 is a fragmentary perspective detailed view of the base portion of the nozzle element of 15 Figure 7;

Figure 9 is a horizontal sectional view taken substantially upon the plane of the section line 9—9 of Figure 7;

Figure 10 is a fragmentary elevational view, 20 parts being shown in section, in an exploded position of a further modification of the invention; and,

Figure 11 is a horizontal sectional view taken substantially upon the plane of the section line 25 11—11 of Figure 10.

Referring now more particularly to the accompanying drawings wherein like numerals indicate similar parts throughout the various views, reference is made first to the embodiment of Figures 1—6, wherein 10 designates generally a complete syringe assembly which as shown consists of a base member 12 upon which is detachably secured a nozzle member 14.

As shown thus in Figure 4, the base member 12 35 comprises a body portion whose upper end terminates in an outwardly flaring, dished, cup-shaped shield or rim 16, which is adapted to conform generally to the contour of the human body about the vagina or another body cavity for water tight

40 sealing engagement therewith, this shield portion being provided at its lower end with an annular reservoir or liquid collecting chamber 18. At its inner or lower end, this chamber or reservoir 18 is provided with a shoulder portion 20 which is screw threaded as at 22 internally thereof. Extending outwardly of the body portion 12 from the shoulder portion 20 thereof, is an axially disposed concentric bore 24 whose bottom wall 26 tapers downwardly and discharges into a longitudinally extending fluid discharge passage 28 which may be detachably connected to a flexible conduit or the like 30.

The body portion 12 is preferably provided axially thereof with a concentric integral upwardly extending sleeve like portion 32 whose

upper end 34 terminates a considerable distance above the upper extremity of the shield 16. As will be seen by reference to Figures 4 and 6, the bore 24 and sleeve 32 define an annular sleeve like passageway 36 constituting a fluid discharge passage.

As will readily be seen by reference to Figures 4 and 6, the discharge passage 28 is eccentric with respect to the axis of the body 12, and with respect to the axis of the bore 24, to give adequate area to the inlet and outlet passages of the body. The tubular sleeve 32 at its lower end communicates with a transversely disposed fluid inlet passage 38 with which may be detachably connected a flexible fluid conduit 40.

It should be here noted that if desired, a conventional type of collapsible rubber bulb may be employed in place of the conduit 40, or 30 as desired; or if preferred manually or automatically operated pump means may be provided for supplying and withdrawing fluid through the passages 38 and 28 as desired.

A detachable nozzle member is received in the threaded bore 22 of the body member, such nozzle being indicated at 14. However, it is to be distinctly understood that various types and constructions of nozzles may be employed, depending upon the nature of the cleansing operation to be performed.

Preferably a nozzle 14 is provided with an elongated body which may be of hollow tubular construction, and provided with a bulb head or upper end portion 42. The nozzle adjacent its head or end is provided with a plurality of appropriately positioned orifices 44 for emitting fluid in the form of a spray in treating a patient.

At its lower end, the nozzle is provided with an outwardly flaring portion 46 which is externally threaded at its lower extremity as at 42 for cooperative engagement and attachment with the threaded bore 22 for removably attaching the nozzle and the body member 12. Slightly above the threaded extremity, the base of the nozzle is provided with a plurality of longitudinally extending circumferentially spaced slots 50 which are positioned to register with the fluid collecting reservoir or chamber 18, and also with the space above the chamber but within the upper rim of the shield 16. These longitudinal slots communicate directly with the annular chamber 36 in the body member 12. As shown in Figure 4, the nozzle 14 is provided with an axial fluid discharge bore 52 this bore opening from the shoulder portion 54 of enlarged diameter in the base of the nozzle, this shoulder portion being adapted to abut in fluid tight sealing engagement with the upper end of the axially extending sleeve 32 at the upper surface 34 thereof.

From the foregoing, it is believed that the manner of operating the device will be readily understood. After the syringe is inserted into a body cavity, with the shield 16 in fluid tight engagement with the surrounding body area, a douche or liquid medicament may be injected either manually or by power means through the inlet end 38, of the axial bore of the inlet sleeve 32, into the nozzle bore 52 and from the spray apertures 44. This discharge fluid after performing its purpose, drains back and is collected upon the shield member 16 being drained thereby into the reservoir or receiving channel 18, and passing through the apertures 50 into the annular discharge passageway 36, from the inclined lower end 26 of which it emerges into the outlet 28, where it is withdrawn either by gravity

or by pump means through the flexible conduit 30.

It should be distinctly noted that the use of this instrument permits a continuous flow of fluid through the inlet nozzle, and a return or discharge of the spent or used fluid without interruption. At the same time, the shield 16 prevents leakage of this fluid thereby promoting the convenience of use of the instrument. The construction is so designed that the nozzle 14 can be readily removed, for great ease and efficiency of cleaning, and all of the passage parts thereof may be readily sterilized and cleaned after each use of the instrument.

Attention is next directed to the form of the invention disclosed in Figures 7-9, wherein a generally similar type of construction is provided. Thus, a body portion 60 having a shield 62 fixed to its upper end, a transverse inlet conduit 64 and a longitudinally extending and depending outlet conduit 66 is provided, the body having a centrally disposed tubular axially extending sleeve member 18 extending above the upper top side of the shield 62. As so far described this construction is identical with that of the preceding embodiment. The nozzle 68 provided with a head 70 having apertures 72 and a longitudinally extending bore 74 is enlarged at its lower end as at 76 for engagement with the upper end of the axially extending sleeve 18 and for sealing engagement in the recess seated at the bottom of the annular collecting chamber or reservoir 83 within the shield member 62. This nozzle is likewise similar in function and construction as so far described to that of the preceding embodiment.

This form of the invention differs from that of the preceding embodiment however in that the enlarged portion 76 of the nozzle terminates in a cylindrical sleeve 84 which is longitudinally notched or slotted at the lower end thereof in peripherally spaced arrangement as at 82 and which sleeve 84 is adapted at its lower end to have a fluid tight sealing engagement upon the bottom of the shoulder portion 80. As in the foregoing embodiment, the slots 82 register with the annular fluid discharge passage in the body 60 and with the collection reservoir 83. In this form however, the sleeve 84 is provided with an internal threaded bore 86 whose upper end is provided with a shoulder or wall 88 adapted to have fluid tight sealing engagement upon the upper end of the sleeve 18, while the threaded portion 86 registers with corresponding external threads 88 upon the utmost extremity of the sleeve 76.

In both forms of the invention, the passages 62 and 74 in the nozzle are adapted to register with and form a continuation of the vertical fluid inlet passage in the sleeves 32 and 18.

In the second form of the invention, the retaining means is thus formed within the bore of the nozzle and upon the upper end of the upwardly extending sleeve, while the lower end of the nozzle forms a sealing engagement with the lower end of the fluid collecting reservoir in the body portion. In the first form of the invention, on the other hand, the fastening in this position at the lower extremity of the nozzle, and in the body portion itself, while a fluid tight sealing engagement is provided between the upper end of the upwardly extending sleeve at a suitable shoulder within the enlarged portion of the nozzle.

From the foregoing, it will be readily seen that there has been provided a simplified construction of a surgical syringe for spraying bodily cavities

which may be easily disassembled for thorough sterilization of its components, may be readily provided with interchangeable nozzles to meet various situations, and which is so constructed as to effectively enable a patient to satisfactorily and conveniently perform various treatments upon his or her own person.

A still further modification of the invention, having quicker and easier fastening means is shown in Figures 10 and 11. This modification is substantially identical with that disclosed in Figures 7-9, differing therefrom by substituting another type of threaded connection. Thus, a base 90 is provided with the concave shield 92 from which axially protrudes the tubular sleeve 94, engageable in the detachable nozzle 96 having axially extending notched terminal fingers 98. Within the bore of the nozzle 96 are provided a plurality of segmented or broken threads 100, cam surfaces or the like for locking engagement with corresponding members 102.

The construction and operation of this form of the invention is otherwise the same as of the embodiment of Figures 7-9.

Since various modifications will readily occur to those skilled at the art after a consideration of the foregoing specification and attached drawings, it is not intended to limit the invention to the exact arrangement shown and described, but all suitable modifications may be resorted to falling within the scope of the invention claimed.

What is claimed as new is as follows:

1. A syringe for treating with fluids a body cavity, comprising a body having concentric inner and outer sleeves defining inner and outer fluid passages, fluid supplying means and fluid withdrawing means each communicating with one of said passages, a shield integrally carried by the upper end of the outer sleeve for fluid tight engagement with the area contiguous to a body cavity, a nozzle having a longitudinal duct therein terminating in an enlarged bore and an enlarged end portion detachably supported on said outer sleeve, said inner sleeve extending above said outer sleeve and having its upper surface seated in sealing engagement in said enlarged bore, said duct communicating with and forming a continuation of said inner passage, a fluid col-

lecting channel in said shield and means in said enlarged portion establishing communication between said channel and said outer passage, said fluid withdrawing means including an outlet conduit eccentric to said sleeves, said outer passage having an inclined bottom wall sloping toward said outlet conduit.

2. A syringe for treating with fluids a body cavity, comprising a body having concentric inner and outer sleeves defining inner and outer fluid passages, fluid supplying means and fluid withdrawing means each communicating with one of said passages, a shield integrally carried by the upper end of the outer sleeve for fluid tight engagement with the area contiguous to a body cavity, a nozzle having a longitudinal duct therein terminating in an enlarged bore and an enlarged end portion detachably supported on said outer sleeve, said inner sleeve extending above said outer sleeve and having its upper surface seated in sealing engagement in said enlarged bore, said duct communicating with and forming a continuation of said inner passage, a fluid collecting channel in said shield and means in said enlarged portion establishing communication between said channel and said outer passage, the internal wall of said outer passage being laterally enlarged at its upper end and opens into the bottom of said channel, said enlarged portion being seated in the laterally enlarged part of said outer passage, said means comprising longitudinal slots in said enlarged portion and extending to the end thereof, said slots establishing continuous and free communication between said channel and said outer passage.
